UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

TAKE-UP MECHANISM FOR SEWING-MACHINES.

1,144,498.

Specification of Letters Patent. Patented June 29, 1915.

Application filed February 27, 1908. Serial No. 418,079.

To all whom it may concern:

Be it known that I, LANSING ONDERDONK, a citizen of the United States, residing at New York city, in the county of New York, 5 State of New York, have invented certain new and useful Improvements in Take-Up Mechanism for Sewing-Machines, of which the following is a description, reference being had to the accompanying drawing and 10 to the letters and figures of reference marked thereon.

My invention relates to new and useful improvements in take up mechanisms for sewing machines, and more especially to a 15 sewing machine having a vertical looper support with a looper moving substantially in a horizontal plane, such as shown in my co-pending application Serial No. 382,899, filed July 9th, 1907, although from certain 20 aspects, it is obvious that my invention may be applied to machines of other types.

The object of my invention is to provide a take up mechanism which shall be durable, simple in construction, and especially adapted 25 for coöperation with a looper moving about a vertical axis.

My invention consists in the parts, arrangements and improvements hereinafter shown, described and pointed out in the 30 claims.

In the drawings which show by way of illustration, one embodiment of my invention: Figure 1 is a top plan view of the work support of a sewing machine, with 35 parts broken away and parts in section to show a looper mechanism with my improved take up cam applied thereto. Fig. 2 is a front elevation with parts broken away to show the looper and take up cam. 40 Fig. 3 is a detail perspective view of the looper support, with my take up cam applied thereto. Fig. 4 is a detail perspective view of the thread guides coöperating with the take up cam.

45 The bed plate 1 of the sewing machine, is of the usual construction, and has rising therefrom, the overhanging arm 2. Supported upon said overhanging arm, is the usual needle mechanism. The looper 3, as 50 herein shown, is mounted on a vertical looper support 4, which is mounted in suitable lugs 5, 5, formed in a bracket 6, secured to the under side of the machine.

The needle is represented at 7, in Fig. 1,

and it will be seen that the looper in its 55 oscillation, will move in a curved path close to the needle, so that the point of said looper will enter the needle loop and pass around into a position so that the looper thread running from the eye of the looper 60 to the previous needle puncture will be properly positioned for the needle to pass between said looper thread and the looper body. Said looper in the present illustration of my invention, is oscillated from a 65 lever 8 which is connected to an arm 9, secured to the looper support by means of a link 10. The lever 8 is oscillated from a link 11, through suitable connections with the main shaft.

70 My improved take up cam 12, is shaped preferably substantially in the form of an ellipse and is secured to the looper support, at one end of the major axis of said ellipse. The curve at the other end of said ellipse 75 is slightly sharpened as shown in the drawings.

The take up cam in the present embodiment of my invention, is shown as formed of a narrow continuous strip for the sake 80 of lightness, although it is obvious that said cam member may be a solid disk. The take up cam 12 is preferably secured to a collar 13, which in turn may be secured to the looper support, so as to swing therewith. 85 Said take-up cam is adjustably secured to the looper support by a screw 13a.

Coöperating with the take up cam, is a thread guiding member 14, which has its shank perforated as at 15, whereby the 90 same may be secured by suitable screws to the under side of the work support. Said member 14 is provided with forwardly extending spaced arms 16, 17. The arm 16 is provided with a thread eye 18 and a thread 95 slot 19, leading thereto. The arm 17 is provided with a thread eye and a thread slot 21 leading thereto. The thread slots 19 and 21 are preferably disposed in opposite directions, so as to properly hold the thread 100 in the thread eye. The thread for the looper as it comes from the supply, is led through a thread eye 22 in a guiding plate 23 set into a recess in the work support, and then along underneath said plate to the 105 forward end thereof. The thread passes from the forward end of the thread guide or cover plate 23, to the thread guide 20 in

the member 17, and thence through the thread guide 18 in the member 16, to the looper. It will therefore, be seen that all pull on the thread from the stitching point, 5 will tend to draw the thread into the thread guides in the member 14. The thread guiding member 14 is preferably so located relative to the take up cam 12, that said cam oscillates between the members 16 and 17 10 and is thus brought into contact with the thread passing through the thread eyes 18 and 20.

As the looper moves forward into the needle loop, the arm 12^a of the take up cam, 15 will engage the thread and force the same away from a straight line connecting the thread guides 18 and 20, until the nose 12^b of the thread cam, slips by the thread. As the looper moves in the opposite direction, the 20 arm 12^c of the take up cam will engage the thread and push the same away from the thread eyes, until the nose 12^b of the cam again slips from the thread. As the looper moves forward, therefore, the take 25 up cam engages the looper thread, and as the looper thread is under strain at this time, by reason of the forward movement of the looper, a small amount of thread is drawn from the supply. As the looper is 30 retracted, the take up cam again engages the thread and takes up the slack in the looper thread and also assists in drawing the looper thread properly for the setting of the stitch.

35 It will be seen that I have therefore, provided a take up cam which is extremely durable and simple in operation and after being properly timed with the looper, the same is not liable to get out of timing therewith. The slots 15 in the shank of the thread guiding member, may be elongated so that said thread guiding member may be adjusted toward and from the axis of the looper, about which the take up cam oscillates for the purpose of varying the amount 45 of thread controlled.

Having thus particularly described my invention, what I claim as new and desire to secure by Letters Patent is:—

50 1. The combination with a thread carrying looper, of a take-up cam therefor moving about a vertical axis, thread guides co-operating with said take-up cam, and means for moving said cam in unison with said looper, said take-up cam being shaped so as to take up the looper thread when the looper is moving forward into the needle loop and also to take up the looper thread when said looper is being retracted from the needle 55 loop.

60 2. The combination of a looper, a vertical support therefor, means for oscillating said looper support, a take up cam mounted to move with said looper, thread guides co-operating with said take up cam, said take

up cam being so disposed as to engage and release the thread in each direction of movement.

3. The combination of a looper, a looper support, a take up cam secured to said looper support at a point adjacent the looper, spaced arms having thread guides therein co-operating with said take up cam, said take up cam being so shaped and disposed relative to said thread guides that the looper thread is engaged and released in each direction of movement of said take up cam.

4. The combination with a looper, a vertical support therefor, means for oscillating 80 said looper, of a take up cam carried by said looper support, spaced thread engaging arms co-operating with said take up cam, each of said arms being provided with a thread eye and a thread slot leading to said 85 thread eye, said thread slots being oppositely disposed in said arms.

5. The combination with a looper, a vertical support therefor, a take up cam which is substantially elliptical in outline and 90 thread guides co-operating with said take-up cam, whereby first one side of said take up cam engages said looper thread and then the other side of said take up cam engages said thread.

95 6. The combination of a looper, a vertical support therefor, means for oscillating said looper, of a take up cam moving about a vertical axis, thread guides co-operating with said take up cam, said take up cam being 100 so disposed relative to said guides that said take up cam engages the looper thread and draws upon the same in each direction of movement of the looper.

7. The combination of a looper moving 105 about a vertical axis, of a take-up cam moving about a vertical axis, thread guides co-operating with said take-up cam, said take-up cam operating to take up the looper thread as the looper is retracted and to pull 110 thread from the supply as the looper moves forward.

8. The combination of a needle, a looper mounted to oscillate in a horizontal plane, means for oscillating the looper and a take 115 up cam oscillating about the same axis but on the opposite side thereof from the looper.

9. In a sewing machine, a vertically operating needle, a looper co-operating therewith, and oscillating about a vertical axis, 120 and a horizontally disposed take-up cam acting on the looper thread in a horizontal plane below the looper.

10. In a sewing machine, a needle and a looper, a support for said looper, means to 125 secure said looper to said support, a take-up carried on said support and having a vertical adjustment thereon.

11. A take up cam for sewing machines including a thread engaging member cut 130

away centrally and shaped so as to form substantially the outline of an ellipse whereby said take up cam is relieved of excessive weight.

5 12. A take up cam for sewing machines, including a thread engaging member cut away centrally and shaped so as to form substantially the outline of an ellipse whereby said take up cam is relieved of excessive weight, a support for said take up cam located at one of the foci of the ellipse.

10 13. In a sewing machine, a needle, a looper, a looper support, a take-up cam carried by said support, thread guides coöperating with said take-up cam, and means whereby said thread guides may be adjusted.

15 14. The combination of a thread carrying implement and a thread controller therefor, including an oscillating shaft, a controlling member carried by said shaft and having a cam shaped thread engaging surface, thread guides for the thread located respectively on

opposite sides of said controlling member, said cam shaped thread engaging surface being so disposed relative to the thread 25 guides and timed as to take up the thread twice for each complete oscillation of said controlling member.

15. The combination with a looper, a looper shaft, means for oscillating said 30 shaft, a take-up member mounted on said shaft, and thread guides for guiding the thread to the looper and into the path of the take-up member, said take-up member having a cam projecting surface adapted to 35 take up the thread twice for each complete oscillation thereof.

In testimony whereof I affix my signature, in presence of two witnesses.

LANSING ONDERDONK.
